UNITED STATES PATENT OFFICE.

NELSON J. TUBBS, OF LOUISVILLE, KENTUCKY, ASSIGNOR OF ONE-HALF TO
R. HARRY SMITH AND ISAAC S. HARTLEY, OF LOUISVILLE, KENTUCKY.

DEVICE FOR DISINFECTING TELEPHONES.

SPECIFICATION forming part of Letters Patent No. 743,353, dated November 3, 1903.

Application filed March 18, 1903. Serial No. 148,388. (No model.)

To all whom it may concern:

Be it known that I, NELSON J. TUBBS, a citizen of the United States, and a resident of Louisville, in the county of Jefferson and State 5 of Kentucky, have invented a Device for Disinfecting Telephones, set forth in the following specification.

This invention relates to telephones, and is more especially an improvement in disinfecting devices for the receiver and transmitter 10 of such sound-conveying instruments.

It is a well-known fact that certain forms 15 of disease, as diphtheria, smallpox, consumption, and kindred diseases, are due to the introduction into the human body of germs or micro-organisms, as bacteria, and their subsequent multiplication and that the atmosphere may become contaminated or infected with such disease germs from the 20 breath of a diseased person, resulting in the spread of disease. It is obvious, therefore, that the general use of telephones, and especially public telephones, provides a medium by which contagious and infectious 25 diseases may be readily communicated from a diseased person using a telephone to others who may subsequently use it, for it has been found that the mouthpieces of telephone-transmitters form excellent repositories for 30 many specific forms of micro-organisms and that the earpiece or receiver is fraught with danger of contamination by reason of its coming into contact with the ear of every one using the telephone.

35 It is the object of my invention, therefore, to provide a means entirely automatic in operation which will thoroughly and most effectually disinfect both the receiver and transmitter of the telephone, so that should any 40 disease germs or micro-organisms be introduced into these parts they will be exterminated; also, to cleanse said parts in such manner as to relieve them of the very unpleasant and nauseous smell which one finds associated 45 with public telephones.

With the above objects in view my invention consists in the employment of means for applying heat directly to the receiver and transmitter of a telephone for exterminating

micro-organisms and purifying said parts of 50 the telephone, together with a thermostatic device for automatically extinguishing said heating means.

The invention further consists in means for applying heat directly to the receiver and 55 transmitter of a telephone for the purpose specified, together with devices for automatically lighting said heating means by the same movement that cuts out the local receiver and transmitter and restores the bell-coils to the 60 main-line circuit, together with a thermostatic device for automatically extinguishing said heating means.

The invention further consists in the particular construction and combination of parts, 65 all as hereinafter fully described, and more specifically set forth in the appended claims.

In the accompanying drawings, which form a part of this specification, Figure 1 is a front elevation showing the application of my invention to a telephone of the type commonly known as "desk-telephones." Fig. 2 is a side elevation of Fig. 1. Fig. 3 is a longitudinal sectional view, enlarged, through the casing which contains the heating device and means 70 for lighting and extinguishing the same. Fig. 4 is a side elevation of said casing, showing the means for operating the main shaft of the lighting and extinguishing devices through the medium of the hook that supports the receiver of the telephone. Fig. 5 is a detail view.

Similar letters of reference indicate similar parts in the several views of the drawings.

It will of course be understood that I have 85 merely shown the invention in connection with a desk-telephone as an instance of its use and that therefore the invention is not limited to its application to this type of telephone.

Referring to the drawings, A designates the standard of the telephone, a the transmitter hinged to the upper end of said standard, a' the pivoted supporting-hook, and a² the receiver or ear-trumpet, which parts are of the 95 usual construction.

In carrying out my invention and for the purpose of directing currents of hot air or

other fluid capable of exterminating micro-organisms into and upon such parts of the transmitter as are likely to receive such micro-organisms the said transmitter is provided 5 with a chamber *b*, surrounding the mouth-piece and formed by a covering-plate *B*, preferably mica, which is held in place by screws. This annular chamber *b* communicates with the mouthpiece through apertures *b'*, which 10 latter permit the hot air or fluid to pass out through the mouthpiece and purify the inner surface thereof. At the lower end of the covering-plate *B* is an elongated socket *b*², in which plays a ball *c* on the upper end of a 15 tube *C*, through which the hot air or fluid is conveyed from the heating device, said ball-and-socket connection permitting of the usual adjustments of the transmitter.

The ear-trumpet or receiver *a*² is of the usual 20 construction, no change being required in the same, inasmuch as when placed upon the hook the outer end or earpiece is located directly over a heat-radiating surface, hereinafter described.

25 *D* designates a casing which supports the heating device and operating means therefor, the said casing being attached to the base of the standard *A*, and to the upper end of the former is pivotally connected the tube *C*, 30 leading to the transmitter, while at the rear end thereof is connected a circular drum *D'*, having a mica cover disposed to be directly under the ear-trumpet *a*² when the latter is suspended from the hook *a'*.

35 In the present instance gas is employed as the medium for generating heat to disinfect the telephone, and, as shown in the drawings, a cock or burner *E* is located in the casing *D* and provided with an extended nipple *e* for 40 connecting a supply-pipe thereto. The plug of the cock or burner, which may be an integral part of the nipple, has secured thereto levers or arms *e'* and *e*², projecting in opposite directions and forming the means by 45 which said plug is operated. The lever or tappet-arm *e'* is operated by a tappet-wheel *f*, located on the outer end of a main shaft *F*, having bearings in the sides of the casing, said shaft being operated by a ratchet-wheel 50 *f'* on its other end, with which ratchet-wheel engages a spring-actuated pawl *g*, carried at one end of a centrally-pivoted lever *G*. To the other end of this lever is connected a rod *g'*, connected to and extending from the hook *a'* of the telephone, the parts being so adjusted that when the receiver is placed on 55 said hook the ratchet-wheel will be moved to turn the plug, through the intervention of the tappet-wheel and arm, and bring the aperture in the plug to register with the aperture in the burner, turning on the supply of gas. In order to provide for lighting the burner simultaneously with the operation of turning on the gas, a second tappet-wheel *H* is mounted 60 on the main shaft within the casing and

provided with peripheral teeth *h* for feeding a strip *I* of percussion-caps over an anvil *e*³, formed on the burner, and to strike off these caps at the proper time a spring-metal bar *I'* projects over the anvil and has a point *i*, adapted to strike upon said anvil, the said spring-metal bar being extended across the face of the tappet-wheel *H*, so that it will be raised by the tappets *h'* thereof.

It will be here understood that instead of 75 providing a percussion-tape any other form of lighting device may be used—for instance, an ordinary electric sparker; also, that any other form of heating device may be provided where it is not convenient to employ gas. 80

In order to provide for automatically shutting off the gas after it has burned for a predetermined length of time, I provide a thermostatic device, which in the present instance consists of a cylinder *J*, having a piston *j* 85 working therein and operated by a body of mercury, (indicated by the letter *s*,) the said piston being connected to the intermediate portion of a lever *M*, which is pivoted at one end to the casing and connected at its other 90 end by rod *m* to the lever or arm *e*², projecting from the burner. The expansion of the mercury by the heat of the burner will operate the piston to shut off the cock, and the adjustment of this thermostatic device with 95 regard to location, &c., may be such as to determine the length of time the gas shall burn.

It is intended that the mechanism hereinbefore described shall be operated automatically by the movement of the hook *a'* in the 100 operation of the telephone. For instance, when the hook is removed the rod *g'* will be lifted, shifting the lever *G*, so that the pawl *g* carried thereby will be moved into engagement with the next tooth of the ratchet-wheel 105 *f'*, and after the telephone has been used and the receiver replaced on the hook the downward movement of the latter, through its connection with the ratchet-wheel *f'*, will turn said ratchet-wheel the distance of one tooth, 110 and this movement being communicated to the shaft will turn the same sufficiently to operate the tappet-wheel *f* to turn on the supply of gas and also the tappet-wheel *H* to feed a fresh percussion-cap onto the anvil 115 and operate the spring-metal bar to explode said cap, whereby the gas is lighted. The heat from the flame goes up the tube *C*, so as to disinfect the transmitter, and a supply passes into the drum *D'* to disinfect the 120 receiver or ear-trumpet located directly above the same, a current of hot air being induced into the drum by providing the vent-opening *v* at the outer end of said drum. It will be found that the heat from the flame will be 125 sufficient to destroy or exterminate any micro-organisms that may have been transmitted to the parts of the telephone by the party previously using the same and that the gas need burn only a minute or two. When the 130

heat has reached a certain degree, the thermostatic device will operate to automatically cut off the supply of gas to the burner, and consequently extinguish the flame. The heat supplied to the receiver and transmitter of the telephone will not only thoroughly disinfect these parts, but will also purify them of any noxious odor.

It will be understood that the transmitter and receiver of the telephone are thoroughly disinfected immediately after it is used by each person and that the disinfecting operation takes place immediately after the receiver or ear-trumpet is placed on the hook.

15 It will also be noted that the application of the devices hereinbefore described does not in any way interfere with the ordinary use of the telephone and needs no attention whatever, being entirely automatic in operation.

20 If necessary, such parts of the transmitter and also the receiver which are in direct contact with the heated air or vapor and liable to injury thereby may be provided with an asbestos lining.

25 Having thus described my invention, what I claim as new, and desire to secure by Letters Patent, is—

1. An apparatus for disinfecting telephones, comprising a heating device and conduits 30 leading therefrom to the receiver and transmitter of the telephone, together with means for lighting and extinguishing the heating device and operated automatically by a movable part of the telephone.

35 2. An apparatus for disinfecting telephones, comprising a heating device, a chamber around the transmitter, a tube leading from the heating device to said chamber, and means for lighting and extinguishing the heating device and operated automatically.

40 3. An apparatus for disinfecting telephones, comprising a heating device for supplying heat to the receiver and transmitter, means for lighting said heating device, and a thermostatic device for automatically extinguishing the heating device.

45 4. An apparatus for disinfecting telephones, comprising a heating device for supplying heat to the receiver and transmitter, means for lighting said heating device operated from a movable part of the telephone, and a thermostatic device for automatically extinguishing the heating device.

55 5. An apparatus for disinfecting telephones, comprising a heating device and conduits leading therefrom to the receiver and transmitter, means for automatically lighting said heating device operated from a movable part of the telephone, and a thermostatic device for automatically extinguishing the heating device.

60 6. An apparatus for disinfecting telephones, comprising a heating device and conduits leading therefrom to the receiver and transmitter, means for automatically lighting said

heating device and operated by a movable part of the telephone, and a thermostatic device for automatically extinguishing the heating device consisting of a cylinder containing mercury and a piston the latter being connected to the aforesaid heating device.

7. In an apparatus for disinfecting telephones, the combination, of a heating device inclosed within a casing, a chamber around the mouth of the transmitter, a tube connecting said chamber with the heating device or casing, and a drum also connected to the casing and disposed under the suspended ear-trumpet.

8. In an apparatus for disinfecting telephones, the combination, of a heating device inclosed in a casing, a chamber around the mouth of the transmitter connected to said casing, and a drum also connected to the casing and disposed under the ear-trumpet; together with means for automatically operating the heating device.

9. In an apparatus for disinfecting telephones, a casing having conduits leading therefrom to the receiver and transmitter of the telephone, a burner or cock located in said casing, means for operating said burner or cock, and a sparking device located adjacent the burner and operated simultaneously therewith.

95 10. In an apparatus for disinfecting telephones, a burner or heating device, a sparking device located adjacent thereto, and means for operating said devices automatically upon the movement of the hook in removing the ear-trumpet therefrom and replacing it thereon.

11. In an apparatus for disinfecting telephones, the combination, of a burner or heating device, a sparking device located adjacent thereto, a shaft having tappet-wheels adapted to operate the burner and sparking device, and means for operating said shaft from the hook of the telephone.

110 12. In an apparatus for disinfecting telephones, the combination, of a burner or heating device, a sparking device located adjacent thereto, a shaft having tappet-wheels adapted to operate the burner and sparking device, and ratchet-and-pawl mechanism actuated by the hook which supports the receiver of the telephone.

120 13. In an apparatus for disinfecting telephones, the combination, of a burner or heating device, a sparking device located adjacent thereto, a shaft having tappet-wheels adapted to operate the burner and sparking device, and ratchet-and-pawl mechanism connected by rod to the hook which supports the receiver of the telephone; together with conduits leading from the burner or heating device to the transmitter and receiver.

125 14. In an apparatus for disinfecting telephones, the combination, of a burner, a sparking device located adjacent thereto, a shaft having tappet-wheels adapted to operate the

burner and sparking device, a ratchet-wheel on the shaft, and a pawl operated by the hook which supports the receiver of the telephone; together with a thermostatic device connected to the burner and operating to automatically extinguish the same.

In testimony whereof I affix my signature

to this specification in the presence of two subscribing witnesses.
